CLAIM

The ornamental design for a motor driven valve, as shown and described.

DESCRIPTION

FIG. 1 is a perspective view of the motor driven valve;

FIG. 2 is a front elevation view of the motor driven valve, the rear elevation view being a mirror image thereof;

FIG. 3 is a top plan view of the motor driven valve;

FIG. 4 is a bottom plan view of the motor driven valve;

FIG. 5 is a left side elevation view of the motor driven valve; and,

FIG. 6 is a right side elevation view of the motor driven valve.
